WALL BRACKET

John H. Balmer, Maplewood, N. J.

Application September 28, 1935, Serial No. 42,565

4 Claims. (Cl. 248—223)

This invention has general reference to wall brackets for attaching various types of fixtures to walls, particularly bath room or kitchen fixtures, such as shelves, towel bars, soap dishes, 5 tumbler holders and the like.

The invention comprehends an improved wall bracket including a base having a recessed rear surface adapted to receive, cover and conceal a slide member rigidly attached to the wall, with 10 interengaging detachable means of connection provided respectively on the base and slide member.

The invention also resides in an improved means of connection between the shank and 15 base of the bracket which facilitates the assembly and disassembly of said parts and permits of the production of a wide range of styles and types of separate fixture shanks and bases which may be assembled in various combinations.

As a further feature the invention contemplates 20 a wall bracket including spring detent means for certain types of fixtures, such as shelves, by virtue of which the fixture is retained on the bracket against accidental or unintentional displacement.

With the above recited general objects in view, 25 other more detail aims will be apparent in the following description and accompanying drawing, while the claims cover variations and modifications falling within the scope of the invention.

In the drawing:

Fig. 1 is a side view illustrating a wall bracket constructed in accordance with the invention.

Fig. 2 is a rear face view of the bracket removed from the slide member.

Fig. 3 is an enlarged vertical sectional view 30 taken approximately on the line 3—3 of Fig. 2, including the slide member and mounted on the wall.

Fig. 4 is an enlarged transverse sectional view 35 on the line 4—4 of Fig. 2, including the slide member.

Fig. 5 is a fragmentary rear face view similar to Fig. 2, with parts removed to disclose the underlying structure.

Fig. 6 is a perspective view of a modified form 40 of slide member.

Referring to the drawing by characters of reference, the wall fixture disclosed by way of illustration is shown as a shelf A which is supported from the wall B by a bracket designated generally by the reference character C. The bracket includes a base 5 and a shank 6, the latter being provided at its free outer end with a hooked terminal 7 adapted to embrace the 45 outer edge of the shelf. This embodiment, how-

ever, is only illustrative of the many other various types of fixtures which the invention is applicable to and is not intended in any way to limit the scope of the invention. The base 5 has a recessed rear surface formed with an undercut beveled portion 8 adjacent the upper end thereof and which is preferably of concave arcuate formation. Within the recessed rear surface of the base 5, a pair of vertically extending guide beads 9 is provided to constitute a guideway in 10 vertical alignment with the undercut beveled portion 8.

A slide member 10 is adapted to be rigidly secured to the wall B by means of screws or equivalent fastening means 11, the heads of which 15 screws are disposed flush or below the outer surface of the slide member. The upper end of the slide member is beveled at 12 and is preferably of convex arcuate formation to cooperate with the arcuate undercut beveled portion 8 of 20 the base 5, while the side faces 13 of the slide member are designed to snugly fit between the guide beads 9, when the recessed rear surface of the base is applied over the slide member and moved downwardly with reference thereto. 25

In order to lock and retain the base of the bracket in assembled relation with the slide, a screw 14 is threaded into a threaded opening 15 in the lower marginal wall 16 of the base, its upper terminal freely engaging within 30 a socket 17 in the lower end of the slide, the head 18 of the screw being counter-sunk in the wall 16. Obviously, upon downward retraction of the screw, upward movement of the base is permitted to disengage the cooperating beveled 35 portions of the slide and base for detaching the bracket and fixture from the wall.

In order to facilitate the manufacture of the base and shank as separate units and to facilitate their assembly and disassembly, the base 40 is provided with a boss 20 protruding from its forward face and the bossed portion is formed with an opening 21 having one or more radial keyways 22, while the shank is provided with a reduced rear terminal 23 having one or more 45 radial keys 24 adapted respectively to fit within the opening 21 and keyways 22. The juncture of the terminal 23 with the remainder of the shank 6 provides a shoulder 25 adapted to fit against the outer face of the boss 20. A screw 50 having a threaded shank 26 is threaded into a threaded bore 27 in the terminal 23 and said screw is formed with an enlarged kerfed head 28 of greater diameter than the opening 21 to retain the shank and base in assembled re- 55

lation, access to the screw being gained through the recessed rear surface.

In the particular adaptation of the invention illustrated, namely, where the fixture is a shelf, 5 detent means may be provided in the form of a lug 30 which is carried by a resilient finger 31 projecting radially from an apertured disc 32 fitted over the screw shank 26 and clamped between the screw head 28 and the inner surface 10 of the forward wall of the base 5 and inner surface of the terminal 23 of the shank 6. In order to provide clearance for the spring finger, the slide member is grooved as at 33 and the forward wall of the base is formed with an aperture 15 34 through which the detent lug 30 projects for exerting a pressure on the rear edge of the shelf A so as to prevent accidental or unintentional displacement thereof. The detent means is desirable on this type of fixture for the reason that the shelves A are usually of plate glass 20 which rest upon and are supported by the shanks 6 and have a tendency to become accidentally displaced by raising the same adjacent the rear edges. In order to overcome this tendency and 25 to frictionally retain the shelf against accidental or unintentional displacement, the spring pressed lug 30 is utilized to exert a frictional pressure on the rear edge. Obviously, in types of fixtures which do not require the detent means, the 30 same may be eliminated as well as the slot 33 in the slide member 10.

In the modified form of slide member illustrated in Fig. 6 of the drawing, the base 35 is provided with a rearwardly projecting anchoring shank 36 adapted to be set in a recess in the wall and secured in place by a plastic material such as cement. The base 35 is of a larger area than the shank 36 so as to cover the plastic material or cement and prevent the same from 40 reaching the forward face 37 of the base. In this instance, the forward face 37 of the base is provided with an upper lug 38 having a beveled upper edge 39 of convex arcuate formation to cooperate with the arcuate undercut beveled portion 8 of the fixture base 5, and a vertical groove 40 to afford a clearance for the detent spring 31. A lower lug or boss 41 is also provided on the forward face 37 of the base 35 and the boss portion is formed with a socket 42 opening through the lower edge thereof to receive the locking screw 14 of the fixture base, said lower lug being adapted to fit between the guides 9 of the fixture base.

What is claimed is:

1. A bracket for wall fixtures including a shank and a base having a recessed rear surface formed with an undercut beveled portion adja-

cent the upper end and a pair of vertically extending guides within said recess, a slide member adapted to be rigidly secured to the wall having side faces adapted to fit between said pair of guides and a beveled upper end adapted to interfit the said undercut beveled portion, and means extending through the lower part of the base and engaging the lower portion of the slide member for detachably securing the base upon the slide member within said recess. 10

2. A bracket for wall fixtures including a shank and a base having a recessed rear surface formed with an arcuate undercut beveled portion adjacent one end thereof and a pair of vertically extending guides within said recess, a slide member adapted to be rigidly secured to the wall having side faces adapted to fit between said pair of guides and an arcuate beveled end adapted to interfit with said undercut beveled portion and means extending through the base and engaging the opposite end of the slide member for detachably securing the base on the slide member within said recess. 15

3. In a bracket for wall fixtures including a base having a recessed rear face and formed with a non-circular aperture constituting a socket, a shank having an inner reduced terminal corresponding in cross section to the shape and size of said socket and adapted to fit within said socket and an outer hooked terminal, a resilient 25 detent located within the recessed fixture base and having a portion protruding forwardly therethrough and projecting outwardly therefrom adapted to cooperate with said outer terminal to retain an article supported by the bracket, and a common means located within the recessed fixture base engaging the fixture bracket shank and the detent for securing the shank and base in assembled relation and anchoring the detent 30 within the base. 40

4. A bracket for wall fixtures including a shank and a base having a recessed rear surface formed with an undercut beveled portion adjacent one end thereof and vertically extending guides within said recess, a slide member including a base and a rearwardly directed shank adapted to be embedded in the wall with the rear surface of the base flush therewith, said slide member having a lower lug on its forward face adapted to fit between the guides and a lug adjacent its upper end having a beveled portion adapted to interfit with said undercut beveled portion of the fixture base, and means extending through the fixture base and engaging the lower lug of the slide member for detachably securing the slide member within said recess. 45
